CLAIM

The ornamental design for a bicycle steering boom, as shown and described.

DESCRIPTION

FIG. 1 is a perspective view of a bicycle steering boom with portions not forming part of the design shown in broken lines.

FIG. 2 is a front side elevation view of the bicycle steering boom of FIG. 1, the rear side elevation view being a mirror image.

FIG. 3 is a top plan view of the bicycle steering boom shown in FIG. 1, the bottom plan view being a mirror image.

FIG. 4 is a left side elevation view of the bicycle steering boom; and,

FIG. 5 is a right side elevation view of the bicycle steering boom.
